[57] CLAIM

The ornamental design for a shower unit, as shown and described.

DESCRIPTION

FIG. 1 is a side perspective view of a shower unit showing our new design;

FIG. 2 is a front elevation view thereof;

FIG. 3 is a side elevation view thereof;

FIG. 4 is a top plan view thereof;

FIG. 5 is a bottom plan view thereof;

FIG. 6 is a rear elevation view thereof; and,

FIG. 7 is an opposite side elevation view thereof.

The broken line showing the hand shower, hose and several fittings is for illustrative purposes only and forms no part of the claimed design.
